UNITED STATES PATENT OFFICE.

EDWARD B. FOX, OF BRYN MAWR, PENNSYLVANIA.

DESIGN FOR A TYPE-BORDER.

SPECIFICATION forming part of Design No. 23,341, dated June 12, 1894.

Application filed February 1, 1894. Serial No. 498,800. Term of patent 7 years.

To all whom it may concern:

Be it known that I, EDWARD B. FOX, a citizen of the United States, residing at Bryn Mawr, in the county of Montgomery and State 5 of Pennsylvania, have invented a certain new and useful Design for Type-Borders, of which the following is a specification.

My invention has relation to printed matter and has for its object the provision of a 10 novel and attractive design for a type border for the same.

The nature of my design appears clearly in the accompanying drawing, the same consisting of a right angled figure whose opposite sides are parallel and formed by straight 15 lines. Two of the four sides of said figure, or the lines which form the lower left hand corner thereof, have each a line of equal length parallel therewith which terminate in planes at the same angle, relatively to the 20 ends of the lines which form the adjacent sides of said figure, as the angle of inclina-

tion of the diagonal lines which occupy the intervening space between them. The effect of which diagonal lines and their alternating spaces being that the lines which form the four sides of the figure appear to be in a higher plane than the parallel lines aforesaid. Conducting to an appearance of thickness and an apparent standing out of the matter contained within the border, as though the same 25 were printed on a block. Forming a striking and attractive border therefor.

What I claim as my invention, and desire 30 to secure by Letters Patent, is—

The design for a type border substantially 35 as herein shown and described.

In testimony whereof I have hereunto set my hand this 26th day of January, A. D. 1894.

EDWARD B. FOX.
